ELECTROLYTIC REDUCTION OF NITRIC
ACID SOLUTIONS CONTAINING RADIO-
ACTIVE WASTE

Henry Ward Alter, Danville, Calif., and Duane L. Barney, Schenectady, N. Y., assignors to the United States of America as represented by the United States Atomic Energy Commission

No Drawing. Application March 8, 1957
Serial No. 644,958

7 Claims. (Cl. 23—159)

This invention relates to a method for the treatment of nitric acid solutions which contain radioactive fission products in a manner that will render the disposal of such radioactive materials both safe and economical. The invention is particularly adaptable to those nitric acid solutions containing fission products resulting from the processing of irradiated uranium fuel as obtained from neutronic reactors. The neutron bombardment of uranium produces valuable products which it is necessary to recover from the remaining uranium and fission products. This is accomplished by either of two methods, one of which involves multiple precipitations and the other a combination of chemical precipitation coupled by solvent extraction. The latter method provides the nitric acid solutions used as the starting material in the present invention.

Disposal of these nitric acid solutions, particularly the radioactive fission products contained therein, presents a very troublesome problem. Direct storage has been suggested, however considerations of the volumes involved, cost of tank space and general safety render such a plan unfeasible. It has also been suggested that the volume be reduced by simple distillation. Such method has not proved successful because certain of the fission products are volatilized from an acid solution during distillation, serious corrosive conditions arise; and unavoidable organic contaminants react explosively with concentrated nitric acid. Another suggested method is to destroy the nitric acid with a reducing agent capable of reacting with the nitric acid to give gaseous products and then reducing the volume of the solution by evaporation. This method has not been used extensively because of health hazards and corrosive problems.

The principal object of the present invention is a method for the treatment of nitric acid waste solutions which will greatly reduce the volume of the radioactive materials to be disposed of. Other objects will be apparent to those skilled in the art upon reading the following description:

In general the process of the present invention involves neutralizing the nitric acid solution with an alkali such as an alkali metal hydroxide, removing the precipitate found and electrolyzing the resulting alkaline nitrate solution which results in the reduction of the nitrate to nitrite ion, ammonia, other gaseous products and converts the alkaline nitrate to hydroxide. The nitric acid solution forming the starting material for the process of the present invention contains about 95% of the fission products produced during the neutron bombardment of uranium and varying amounts of nitrate salts. It will

2

range from 0.5 M to 4 M in nitric acid and from 0.5×10^{-3} M to 2×10^{-3} M in uranium and 0.5 M to 6 M in total nitrates. A typical analysis follows:

HNO ₃	.....	M	1.9
Uranium	.....	M	1.4×10^{-3}
Total β activity	.....	c./m./ml.	1.2×10^7
Total gamma activity	.....	c./m./ml.	5.5×10^6

The complete process of the present invention contemplates three principal steps, neutralization of the waste acid solution to yield an alkaline nitrate solution and a precipitate of hydroxide, which is removed by filtration or otherwise, electrolysis of the nitrate solution to convert the alkali nitrate to alkali hydroxide, and to yield ammonia and oxygen, which incidentally may be converted to nitric acid by well known catalytic methods, and reduction of the volume of the hydroxide solution by evaporation. The resulting hydroxide solution can then be recycled to act as the base for neutralizing additional waste acid.

More specifically, the nitric acid waste is neutralized by alkali hydroxide in an amount sufficient to render the solution 0.2-2 M in hydroxide which precipitates uranium hydroxide providing a scavenging agent for the fission products present in the nitric acid. Uranium normally present as a loss from the previous separation process acts as the scavenger, however if desired, small additions of metal salts of the order of .01 g. to 1 g. per liter, the metal ion of which will precipitate as the hydroxide in alkaline solution, e. g. ferric nitrate, may be made before neutralization. The bulk of the fission products are removed from the solution along with the precipitated hydroxides by hydroclone, centrifuge or by filtration resulting in a gross decontamination factor of 2-10. The alkaline nitrate solution is then electrolyzed in an electrolytic cell, several types of which are available commercially. The gases produced during electrolysis are scrubbed by conventional means and may be released without hazard. However economies prescribe that the gaseous nitrogen products be retained for conversion to other useful products. The reduction of the nitrate results in the formation of an equivalent amount of alkali hydroxide. This basic solution, which may contain undestroyed nitrate and nitrite is evaporated to remove the water and any dissolved ammonia. The distillate which contains only a small amount of dissolved ammonia may be discarded. The concentrated alkaline hydroxide solution is then recycled to the neutralization step.

Accordingly, all scavengable fission products constituting most of the radioactive material, are removed in the precipitation step and since the volume of the precipitate is small, the space necessary for storage is greatly reduced. Non-scavenged fission products, such as ruthenium and cesium will build up on successive recycle to produce a stream rich in specific fission products which may be recovered by ionic exchange or other means not involved in the method of the present invention. Fission products are not volatile in alkaline solution, therefore, adequate safety factors are obtained by mechanical deentrainment such as scrubbing. The fission products removed with the precipitate may be readily and safely stored indefinitely and may if desired be used as a radiation source.

The invention is further illustrated by the following example:

EXAMPLE I

One thousand liters of nitric acid waste solution from the solvent extraction of uranium and plutonium was divided into equal parts. Ten g. of ferric nitrate was then added to one part and both parts were made about 0.25 M in sodium hydroxide. The resulting precipitate of hydroxides was removed by centrifugation. The supernatant solutions gave the following analysis.

	1	2	3	4
NaNO ₃ concentration M.....	4.85	4.85	4.85	4.85
NaOH concentration M.....	0.26	0.26	0.22	0.23
NaNO ₂ concentration M.....	4×10 ⁻⁴	4×10 ⁻⁴	4×10 ⁻⁴	4×10 ⁻⁴

Decontamination factors

	Added Ferric Nitrate	No Ferric Nitrate	
Gross γ	7	6.7	7.1
Gross β	27	28	26
Uranium.....	1.8	1.4	1.4
Strontium.....	5.5	8.1	9.0
Rare earths.....	370	310	390
Ruthenium.....	1.4	1.2	1.1
Cesium.....	1.0	1.0	1.0
Zr+Nb*.....	>400	>400	>400

*A decontamination of 400 represents approximately the lower limit for the detection of Zr+Nb for the analytical method.

The solution was then subjected to electrolysis which was continued until the concentration of the nitrate ion in the solution was reduced to 0.25 M. The solution was then evaporated to 25% of its original volume and the residue returned to the neutralization step in the process.

What is claimed is:

1. A process for the treatment of a nitric acid solution containing radioactive wastes, being substantially 0.5-4 M in nitric acid, which comprises neutralizing the solution with alkali hydroxide in an amount sufficient to make the solution 0.5-2 molar in alkali hydroxide and precipitate insoluble hydroxides, separating the precipitate, electrolyzing the solution to convert the alkali nitrate to alkali hydroxide, gaseous ammonia and oxygen, reducing the volume of the solution by evaporating the water and dissolved ammonia and recycling the concentrated solution.

2. A process for the treatment of a nitric acid solution containing radioactive wastes, being substantially 0.5-4 M in nitric acid, which comprises neutralizing the solution with sodium hydroxide in an amount sufficient to make the solution 0.5-2 molar in sodium hydroxide and precipitate insoluble hydroxides, separating the precipitate, electrolyzing the solution to convert the sodium nitrate to sodium hydroxide, gaseous ammonia and oxygen, reducing the volume of the solution by evaporating the water, and dissolved ammonia and recycling the concentrated solution.

3. A process for the treatment of a 1.9 molar nitric acid solution containing radioactive wastes, which comprises neutralizing the solution with sodium hydroxide in an amount sufficient to make the solution 1.2 molar in sodium hydroxide and precipitate insoluble hydroxides, separating the precipitate, electrolyzing the solution to convert sodium nitrate to sodium hydroxide, gaseous ammonia, and oxygen, continuing the electrolysis until the solution is substantially 0.25 molar in nitrate ion, reducing the volume of the solution 75% by evaporation and recycling the concentrated solution.

4. The process of claim 1 in which .01-1 gram per liter of ferric nitrate is added to the nitric acid solution prior to neutralization.

5. The process of claim 2 in which .01-1 gram per liter of ferric nitrate is added to the nitric acid solution prior to neutralization.

6. The process of claim 3 in which .01-1 gram per liter of ferric nitrate is added to the nitric acid solution prior to neutralization.

7. A process for the treatment of nitric acid solution containing radioactive wastes being substantially 1.9 molar in nitric acid which comprises adding ferric ion as ferric nitrate in an amount sufficient to yield a solution approximately 8×10^{-5} molar in ferric ion, neutralizing the solution with sodium hydroxide in an amount sufficient to make the solution 1.2 molar in sodium hydroxide and precipitate insoluble hydroxides, separating the precipitate, electrolyzing the solution to convert soluble sodium nitrate to sodium hydroxide, gaseous ammonia and oxygen, reducing the volume of the solution by evaporating the water and dissolved ammonia and recycling the concentrated sodium hydroxide.
